UNITED STATES PATENT OFFICE.

TRUMAN A. EDGERLY, OF OKLAHOMA CITY, OKLAHOMA.

PLUNGER FOR PUMPS.

Application filed July 21, 1924. Serial No. 727,236.

To all whom it may concern:

Be it known that I, TRUMAN A. EDGERLY, a citizen of the United States, residing at Oklahoma City, in the county of Oklahoma and State of Oklahoma, have invented certain new and useful Improvements in Plungers for Pumps, of which the following is a full, clear, and exact description.

The invention relates to plungers or pistons for pumping all kinds of liquids or gases, but it is more particularly adapted for use in pumping oil wells.

In pumping oil with the various types of pumps now known there is often much cutting and cracking of the crude oil, thereby materially reducing the value of the oil and in some instances rendering it practically worthless. One of the objects of the present invention is to avoid agitation of the oil or other liquid being pumped, or at least reduce the agitation to a minimum; and I accomplish this by providing a free and unobstructed passage for the oil or other liquid being pumped.

Further objects of the invention are to provide a plunger of this character which is extremely simple in construction and hence relatively inexpensive in manufacture; which will stand hard usage, and which consists of such few parts that there is practically no possibility of parts getting out of order, and consequently there is no occasion for repairs until the packing is worn out.

Other objects and advantages of the invention will be apparent from the following detailed description, when taken in connection with the accompanying drawings, in which:

Figure 1 is a vertical sectional view of a working barrel, and showing an elevational view of my improved plunger arranged therein; the conventional lower or standing valve is also shown, but it forms no part of the present invention.

Figure 2 is a vertical sectional view of the plunger; and

Figure 3 is a fragmentary sectional view, showing the lower portion of the plunger; the plunger being on its upstroke and hence the valve being shown as closed.

Referring to the drawings more in detail, numeral 1 indicates the usual working barrel of an oil well, and mounted in the lower end thereof is the conventional lower or standing valve indicated by numeral 2.

The plunger is referred to generally by

the numeral 3, and it is in the structure of this plunger that the present invention resides. Numeral 4 indicates a tube which extends from the top to the bottom of the device, and mounted on the lower end of this tube is a valve member 5, which is beveled to cooperate with a valve seat in a manner to be described hereinafter. The valve member may be formed integral with the tube 60 4, if desired, but in the drawings I have illustrated the valve member as screw threadedly mounted on the tube. The lower end of the tube, just above the valve member 5, is provided with a plurality of apertures 65 6. There are four of such apertures illustrated in the drawings, but, of course, a greater or lesser number may be employed, as desired.

The upper end of the tube is screw threadedly mounted in a cap member 7. The lower portion of the cap member is hollow to communicate with the interior of the tube 4, and apertures 8 are provided in the cap member to permit communication between the interior of the cap and the interior of the well tubing. Four of these apertures are illustrated in the drawings, but, of course, any desired number may be employed; and it is to be noted that the apertures 8 are larger 70 than apertures 6, the purpose being to permit a free exhaust of the oil, or other liquid, or gas. By having the larger holes at the top it is obvious that there is no possibility of the liquid becoming entrapped, thereby 75 putting an unnecessary load on the pump and also increasing the agitation of the liquid. Screw threadedly or otherwise attached to the top of the cap is the sucker or pump-rod 9.

I will now describe the arrangement of the packing on the tube 4, and the manner in which the plunger valve is opened and closed. A plurality of metallic cup-shaped members 10 are mounted on the tube, and arranged between the metallic members are the fabric cup-shaped members 11. The metallic members are all screw threadedly connected with the fabric members between them, as clearly illustrated in Figure 2. One 80 of the metallic cups forms the upper end of the packing and it is adapted to abut against the shoulder 12 of the cap to limit the movement of the packing member in that direction. Screw threadedly mounted on the 85 lower metallic cup is a valve seat 13 which cooperates with the valve member 5. The

simplicity of this structure is apparent, and it is of very material importance. It will be noted that the packing elements themselves form a unitary structure which is slidable on the tube 4, and thus the necessity for another tube, or similar element, for carrying the packing is entirely eliminated. And it will also be noted that the valve seat is mounted directly on the packing elements, thereby reducing the structure to the utmost simplicity.

The operation of the apparatus will no doubt be clearly understood from the foregoing description of the construction; but it may be briefly described as follows:

Assume the plunger is at the bottom of its stroke and is about to start its upward movement; the relative position of the elements being as illustrated in Figures 1 and 2. When the pump or sucker rod is lifted the tube 4 and valve member 5 move upwardly therewith through the unitary packing member until the valve member 5 engages the seat 13, as clearly indicated in Figure 3, and upon farther upward movement of the pump rod the packing, tube and valve member move upwardly together, thereby lifting and discharging the oil or other liquid above it. At the same time that it is lifting the liquid above it it is also drawing liquid into the bottom of the barrel through the standing valve 2. Now when the plunger is lowered the tube and valve member first move downwardly, unseating the valve and opening the aperture 6; the position of the parts being as illustrated in Figures 1 and 2. As the plunger moves on downwardly the apertures remain open and the oil or other liquid passes through those openings, through the tube 4, and is discharged freely through the larger openings in the cap. The operation is now repeated, the valve being seated, the apertures 6 closed, and the plunger elevated.

In accordance with the patent statutes, I have described what I now believe to be the best embodiment of the invention, but I

do not wish it to be understood thereby as limiting myself or the scope of the invention, as many changes and modifications may be made without departing from the spirit of the invention; all such I aim to include in the scope of the appended claims.

What I claim as new and desire to secure by Letters Patent is:

1. A plunger for pumps, including a cap attached to the pump rod, a tubular member attached to the cap, and a valve member attached to the lower end of the tubular member, said cap provided with apertures always in communication with the interior of the tubular member and the space above the plunger, and said tubular member provided with apertures just above the valve member.

2. A plunger for pumps, including a cap attached to the pump rod, a tubular member attached to the cap, and a valve member attached to the lower end of the tubular member, said cap provided with apertures, and said tubular member provided with apertures just above the valve member, the apertures in the cap being larger than those in the tubular member.

3. A plunger for pumps, including a tubular member, means for attaching said tubular member to the pump rod, communicating means always open between the interior of the tubular member and the space above the plunger, a valve member attached to the lower end of the tubular member, said tubular member provided with apertures adjacent the valve member.

4. A plunger for pumps, including a cap attached to the pump rod, a tubular member attached to the cap, a valve member attached to the lower end of the tubular member, said cap provided with apertures, said tubular member provided with apertures adjacent the valve member, packing elements mounted directly on the tubular member, and a valve seat mounted on the packing elements.

TRUMAN A. EDGERLY.
